US0D1066648S

(12) United States Design Patent (10) Patent No.: US D1,066,648 S
(45) Date of Patent: * Mar. 11, 2025

(54) FACE MASK

(71) Applicant: Honeywell International Inc.,
Charlotte, NC (US)

(72) Inventors: Xiaojin Han, Shanghai (CN); Seven Zhou, Shanghai (CN); Hongbing Xiang, Shanghai (CN); Weifeng Shen, Shanghai (CN); Xia Jin Zhao, Shanghai (CN); Teicheng Qu, Shanghai (CN)

(73) Assignee: HONEYWELL INTERNATIONAL INC., Charlotte, NC (US)

() Term: 15 Years

(21) Appl. No.: 29/949,828

(22) Filed: Jun. 28, 2024

Related U.S. Application Data

(62) Division of application No. 29/803,436, filed on Aug. 12, 2021, now Pat. No. Des. 1,039,133.

(57) CLAIM

The ornamental design for a face mask as shown and described.

DESCRIPTION

FIG. 1 is a first perspective view of a face mask showing the new design, shown in an unassembled configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of the face mask that form no part of the claimed design.

1 Claim, 5 Drawing Sheets
